Filed May 22, 1962, Ser. No. 196,780

14 Claims. (Cl. 107—14)

My invention relates to ring die pelleting machines adapted especially for field use. Hay is picked up from the field surface by any known pick-up apparatus and continually fed to the machine. In such machines, relative rotation between the die ring and the associated rolling means forces the material through the die cells of the ring die to form the pellets. Such machines commonly embody relatively revolvable annular ring die structures and coacting rolling means. Sometimes the ring die revolves about the rolling means; sometimes the rolling means revolves around the ring die; and sometimes both revolve simultaneously. Occasionally the rolling means is comprised of a second ring die means coacting with the first. My invention may be applied in whole or in part to any one of the several forms taken by this type of pelleting machine.

In achieving my invention I have had several aims. These aims are: improvement in the overall efficiency of ring die pelleting machines, better control of pellet density, an increase in the compactness of the machine, ease of assembly, easy repair and replacement of parts, flexibility of adaptation for various capacities, lowered weights and lowered manufacturing costs.

I achieve the aims of lowering the weights and costs not only by efficiency using metal, but also by consolidating and simplifying the die rings and die cell cross section controls; by sectionalizing the ring of dies; by rendering the die sections self-supporting against bursting strains, thus doing away with the need for heavy securing bolts and attendant drillings; and by absorbing the radial force components directly in the rings rather than by way of bolts. Easy assembly, repair and replacement and flexibility of design for various capacity, are also derived from these means.

Increased compactness results jointly from the foregoing and from the vertical arrangement of the rotational axis of the machine.

Better pellet density control is obtained by diverging the axes of adjacent superimposed die cells, rendering the intermediate cell walls relatively adjustable, and arranging a common adjusting means between these juxtaposed intermediate walls.

I obtain increased efficiency by a better infeed distribution achieved jointly through the vertical arrangement of the infeed, improved infeed confining and directing surfaces, and an improved infeed auger system.

A special construction of the die mouth improves charge retention by the die cells, while a special roll peripheral configuration coacts with the special die mouth construction and the divergent arrangement of the die cells to improve the efficiency of compaction of the material in the die cells and its movement therethrough.

The detailed constructions of these features are shown in the accompanying drawings which represent the best embodiment of my invention now known to me and several of the possible modifications which I have envisioned.

In the drawings:

FIG. 1 is a vertical sectional view of the machine of this invention;

FIG. 2 is a fragmentary plan view of the device of FIG. 1 taken on line 2—2 of FIG. 1;

FIG. 3 is an enlarged sectional view taken on the line

2

3—3 of FIG. 1, looking in the direction of the arrows applied to the line, and showing several die cell units;

FIG. 4 is a sectional view taken on the line 4—4 of FIG. 3, looking in the direction of the arrows applied to the line, and showing a single die cell unit;

FIG. 5 is a sectional view taken on the line 5—5 of FIG. 3, looking in the direction of the arrows applied to the line, and showing how two die cell units cooperate to define the actual die cells;

FIG. 6 is a perspective view of one of the die cell units alone;

FIG. 7 is a perspective view of a pellet such as formed by the machine;

FIG. 8 is an enlarged fragmentary sectional view of a modified form of actuating means for the adjustable die cell walls;

FIGS. 9 and 10 are, respectively, diagrams in plan and sectional elevation of a modified form of die cell wall adjusting means, employing extensible and retractable screw means applied to the pairs of juxtaposed intermediate cell walls; and

FIGS. 11 and 12 show semi-diagrammatically, respectively, in elevation and plan, a modified form of the auger infeed.

Dealing now with the overall organization of the machine, it will be seen that the ring die in general is comprised of lower and upper frame side plates, or rings, 20 and 21. Intervened between frame side plates 20 and 21 are a plurality of die cell units 25 arranged in an annular series, or nest, as best seen in FIG. 2. An individual cell unit may be seen in FIG. 6. In assembled form, as shown in FIGS. 1 and 2, the cell units 25 cooperate to define two superimposed annular series, or nests, of die cells, an upper annular series 23 and a lower annular series 22. The die cell units 25 are separable from the frame side plates 20 and 21 and from each other as clearly shown in FIGS. 1, 2 and 3—6. The axes of the cells in the upper series of cells 23 and the axes of the cells in the lower series of cells 22 diverge relative to each other as they progress radially outwardly from the central axis of the machine. This clearly appears in FIG. 1. Portions of the juxtaposed divergent intermediate cell walls are rendered adjustable and provided with adjusting means 24. Coacting commonly with the two annular series of die cells 22 and 23 and embodied into the die ring structure is a pair of relatively revolving rotatable rolls 30 and 31.

The rolls 30 and 31 have peripheries which are revolved and rotated in close proximity to the mouths of the die cells. They are carried by roller bearings 32 borne by pins 33 centered in the outer ends of the bipartite frame 34. Frame 34 is mounted upon the upper end of a main drive shaft 35 which is centered upon the axis of the die ring. The drive connection consists of a circumferential series of hub splines 36. The main drive shaft 35 is journaled in roller bearings 37 and 38 supported, respectively, by the integrally formed web 39 and by the removable cap 40 which closes the lower end of gear casing 41. Gear casing, or housing, 41 is formed as an integral extension of the lower die frame side plate 20. Lower bearing 38 is a combined radial and axial thrust bearing. Bevel gears 42 are contained within casing 41 and are spline connected, respectively, to the main drive shaft 35 and to a laterally projected power shaft 43 extended through bearing housing 44 which is bolted onto casing 41. Bearing housing 44 carries roller bearings for the power shaft 43. Power shaft 43 carries at its outer end a relatively wide multiple V-belt pulley 45. Power for operating the machine is supplied through this train 45 to 35. Gear housing 41 carries an oil bath 46 by means of which all of the associated gears and bearings

3
are lubricated. Appropriate oil sealing devices 47 and 48 are provided where shafts 35 and 43 emerge, respectively, from the gear housing 41 and from the bearing housing 44. An oil slinger 49 distributes oil throughout housing 41.

While the lower die frame side plate 20, with its integral radial and axial gear housing extensions, completely closes off the access from below to the two annular series of die cells 22 and 23, the upper die ring frame side plate 21 has an open inner-periphery substantially of the same diameter as the inner-periphery of the assembled ring of die cell units 25. Through this open periphery, which is designated 50, the material to be pelleted is fed to the machine. The feeding is through a vertically extending cylindrical sheet metal housing 51 which is seated in a metal thickness recess within a vertically extending inner-peripheral flange 52 formed on the upper die ring frame side plate 21. Uniformity of downward feeding and distribution about the mouths of the annular series of die cells 22 and 23 is achieved through the provision of a double flight auger, the respective flights of which are numbered 53 and 54. These are mounted upon and coat with upwardly pointing, flight mounting and material distributing cone structure 55. This cone is mounted upon an upward extension 56 from the main drive shaft 35. A stiffening web 55' welded to the interior of cone 55 is centrally apertured to fit closely over the body of shaft 56, while the point of the cone is also centrally apertured and flattened at 56' to be axially bolted, as shown, to the upper end of the extension 56. Extension 56 is shouldered at 56" and its reduced lower end has a threaded connection with shaft 35.

Intervened between the upper end of hub 57 of bipartite frame 34 and shoulder 56" is a large diametered thick washer 57' which bears down upon the upper end of hub 57 and holds the same firmly in splined driving connection with shaft 35. Hub 57 is axially centrally divided as at 57" thus enabling the upper half of frame 34 to be removed from the lower half and independently freed from shaft 35 after shaft extension 56 is unthreaded and the auger is removed. When this is done, it leaves free the upper ends of pins 33, and rolls 30 and 31 can then be removed and replaced.

The base of cone 55 is of a diameter considerably less than the diameter of the inner periphery 50 of the assembled ring of die cell units 25, thus providing annular space between them. Material progressed downwardly over the surface of the cone by auger flights 53 and 54 is annularly distributed to and about the ring of die cell units through the annular space. The lower margins of the cone are cut out as at 58 to fit down over the sides of the upper half of frame 34 as clearly appears in FIGS. 1 and 2. This provides the main driving connection for the conically based auger.

The machine thus organized to operate in a vertical attitude is adapted for mounting upon a wheel chassis, together with a driving motor, for field use. In FIG. 1, is shown certain channel members designated the left 97 and the right 98, bolted to the sides of the gear casing 41 and thereby affording ample based rigid support from the field chassis of which members 97 and 98 are a part. The right hand channel member 98 engages a pad formed integrally with the right hand side of the gear housing 41. The left hand member engages under the heads of the same bolts which secure the bearing housing 44 to the left side of the gear housing 41. A suitable aperture in the bottom of the channel serves to pass the bearing housing therethrough.

It is outstandingly in the construction and arrangement of die cell units 25 that the other aims of this invention are achieved; though, as will be seen, other elements of the machine make their contribution in some degree. The terms axially and radially as employed herein are with reference to the central axis of the machine as a whole, which is the axis of main drive shaft 35. Referring especially to FIG. 1 and FIGS. 3-6, it will be seen at once

4
that the two superimposed annular series of die cells 22 and 23 are defined by a plurality of identical axially integral die cell units 25. The cell units are annularly arranged about the axis of drive shaft 35 and they abut 5 each other in axially extending radial planes through the main drive shaft axis. These axially extending radial planes, as defined by the dividing lines between abutting integrally formed identical die cell units 25, are designated 60 throughout the drawings. Each such integral unit 25 comprises the radially extending, axially common side wall portion 61 of two superimposed die cells 62 and 63 (see FIG. 5) belonging, respectively, to the superimposed annular series of cells 23 and 22. Integrally formed with and projecting from each side of the wall 61 at both the top and bottom ends thereof is one half of a die cell end wall 64. Integrally formed with and projecting from each 10 side of the wall 61, axially intermediate the half end wall portions 64, is one half of a transaxial intermediate wall portion 65 of the cells 62 and 63. As FIGS. 3-6 make 15 clear, the integrally formed intermediate wall halves 65 extend radially outwardly from the mouths of the die cells only a portion of the length of the side walls 61. Each of the oppositely extending transaxial end wall halves 64 and intermediate wall halves 65 terminate in the axially 20 extending radial planes 60. The planes 60 constitute axially extending planes of symmetry of the individual die cells. Thus, as formed, none of the individual die cell units 25 in and of itself completes a die cell, but as annularly assembled together in abutting relationship in the radial planes 60, they cooperate to form two axially juxtaposed annular series of die cells 22 and 23 independently 25 of the die frame side rings 20 and 21. FIG. 5 of the drawings shows how two abutting cell units 25 cooperate to define a complete cell 62 of upper annular series 23 of cells, and a complete cell 63 of lower annular series 22 of cells independently of the die frame side plates, or rings, 20 and 21.

The cross sections of the cell units 25 are made of such thickness and of such material as to be able to resist the high bursting pressures of the pelleting operation independently of any axial clamping force from side plates 20 and 21. This particularly applies to the cantileverly extending halves of the end walls 64 of the units whose cross section is made particularly heavy. This enables 30 a connection of the die cell units 25 to the die frame side plates 20 and 21 by means of axially extending interengaging integral projections and sockets 70 and 71 between the die cell units and the frame side plates, instead of by the use of heavy through running bolts as has been formerly practiced. There are necessary, but relatively small, bolts 72 threaded into the ends of individual projections 70 and bearing on side plates 20 and 21 through washers; thus, separately and independently securing the side plates 20 and 21 to the annular assemblage of die cell units. This 35 means of securing utilizes the integral main bodies of the die cell units as a tensioning means for tightening the components of the die ring together. The foregoing features of construction conduce especially to simplicity, ease of replacement, ease of assembly, ease of repair and replacement, low weight and low cost of manufacture.

In the control of the density of the pellets through change in cross section of the die cells as the pellets are progressed through them there are likewise utilized the principles of consolidation and identity of parts. In addition there is provided common actuation for the cells of the respective annular series 22 and 23. To further this, the two series of cells 22 and 23 are arranged to axially diverge from each other. The cell mouths 75, in the vicinity of the inner-periphery 50 of the die ring, lie closely adjacent each other, but the discharge ends 76 of the cells lie axially spaced apart. The outer portions 77 of the intermediate cell walls are rendered axially adjustable about transverse axes 78 at their radially inner ends. The inner surfaces of these adjustable walls extend 40 in radial continuation from the inner surfaces of the in-

termidate wall portion 65 as shown by dotted lines in FIG. 1. The pivotal axes 78 are integrally formed projections and sockets between the adjustable intermediate walls 77 and the side walls 61 of the units, as most clearly appears in FIGS. 1, 5 and 6. The diameters of the projections and sockets are so proportioned that they lie side by side within the projected thickness of the intermediate wall portions 65 (FIGS. 1, 4 and 5) and thus do not obstruct or change the uniformity of the cell cross sectional area in this region. The cell cross section is rectangular or square and all of its four corners are rounded as clearly appears in FIGS. 4 and 5 and as indicated by the numeral 79. The rounded corner portions 79 between the end walls 64 and the side walls 61 are formed integrally in the cell units 25. The rounded corner portions associated with the intermediate wall portions 65 and the side walls 61, are also formed integrally with the cell unit; but the rounded corner portions which lie within the length of the adjustable intermediate wall portions 77 are formed integrally with the adjustable wall portions 77 (see FIG. 5). Thus the formed pellet (see FIG. 7) has four rounded corners of approximately the same radius irrespective of changes in the thickness of cross section brought about by relative adjustment of the intermediate walls 77.

The axial divergence of the two annular die cell series 22 and 23 not only provides an intervening space within which the adjustable wall portions 77 may be moved axially toward and from each other to adjust the die cell cross sections, but also provides space for the interposition, between adjustable wall portions 77, of the common operating means 24. Such means shown in the principal figures of the drawings and detailed in FIGS. 3 and 4, comprises the relatively thick-walled rigid tube 85 seated on one side in its annular extent upon the curvilinear terminal extension 86 of each of the adjustable walls 77 of the series 22. Bearing against an identical curvilinear terminal extension 87 of the adjustable walls 77 of the upper series 23 are a plurality of identical pistons 88 extending parallel to the central axis of the machine as a whole and fitted and sealed into apertures 89 communicating with the hollow interior of the tube 85. When fluid pressure is applied to the hollow of the tube 85, the pistons are forced outwardly to react against the terminal extension 87 of the upper intermediate walls 77, and the tube 85 as a whole is reactively pressed downwardly to exert the same pressure upon the terminal extensions 86 on the lower intermediate adjustable walls 77. In forming pellets of high density the hydraulic pressures required are quite high and the stresses which the walls 77 and the adjusting mechanism are subjected are correspondingly high. Not only does the thick walled annular tube 85 carry these pressures, but also the pistons are of proper proportions to develop the actuating pressures needed at each individual cell. The walls 77 themselves are afforded both the cross section and the re-enforcement needed to take care of such pressures. Beside thickness of cross section, increased strength is had by reason of the integral formation of the round corners 79 (FIG. 5) carried by these walls which give them a channel-shaped cross section. In addition, there are provided central longitudinally extending outer re-enforcing ribs 90 which extend from the pivots 78 at radially outwardly increasing depth all the way to the pistons 88 (FIGS. 1 and 5).

A limit to the minimum cross sectional area of the pellets produced is provided in the form of shoulders 91 formed in the outer extremities of side walls 61 and engageable by annular extensions 92 on the adjustable wall terminal extensions 86 and 87. See FIGS. 1, 3 and 6. Limit to the length of pellets is provided by plates 93 secured to the outer surfaces of terminal extensions 86 and 87 of intermediate adjustable walls 77 and projecting angularly into the paths of the exiting extruded material. When the extrusions reach the plates they engage the

plates with a force sufficient to break the extrusion away from the end of the die cell, so forming the pellets.

Efficiency of pellet compaction and extrusion is improved through the axial divergent relationship of the two annular series 22 and 23 of die cells and the complementary surface configuration of the coacting rolls 30 and 31. The axially spaced lips 95 of the end walls 64 at the die mouths 75 are extended radially inwardly beyond the lips of the remaining walls of the die cell units and at the same, or substantially the same, divergent angle as the two end walls 64 of a single cell unit 25. This can be clearly seen from an inspection of FIGS. 3 and 6 in conjunction with FIG. 1. So extended, these lips 95 form a pocketed space the margins of which converge radially inwardly to the inner periphery 50 of the die ring side plate 21. The rolls 30 and 31 enter these spaces almost to touch the lips of the remaining walls of the die units. The roll surfaces are obtusely angled in radial cross section and this angle is such that as the roll peripheries pass over the mouths of the cells between the lips 95, those portions of the roll surfaces juxtaposed, respectively, to the upper and lower annular series of cells 23 and 22 lie at substantially right angles to the divergent lengths of the die cells as shown in FIG. 1. The compacting and extruding forces exerted by the rolls are therefore directed precisely parallel to the line of divergence of the die cells. The masses of material compacted into the mouths of the dies are held strongly within the die mouths by reason of engaging radially inwardly converging lips 95.

The general operation of those ring die pelleting machines is so well understood in the art that it need no description here. When the machine is being operated at the proper speed it is only necessary to continuously feed material into the feed housing 51. It being assumed that the material to be fed is ready for pelleting, the machine will continuously receive, compress, compact and extrude the material through the die cell units. To regulate density one has only to regulate the pressure of the fluid within the hollow of the annular tube 85. The fluid is introduced to the hollow tube 85 through a connecting conduit 100 opening into an area between pistons 88, by way of a suitable control valve (not shown). The plates 93, extending angularly from the outer ends 86 and 87 of adjustable walls 77, are engaged by the outer ends of the extruded material, as its radial extension increases, with the result that extruded masses are broken into pellets as they reach the desired lengths.

Obviously the features of my invention may be modified in part or in whole without departing from the spirit of my invention. For example, the means 24 for actuating the adjustable walls 77, by which the density of pellets is regulated, can be constructed as shown in FIG. 8 by using a flexible walled tube 105 whose opposite sides seat between curved terminal extensions 86 and 87 of the adjustable walls 77. Such flexible tube, as distinguished from the rigid thick wall tube shown in FIGS. 1, 3 and 4, expands and contracts its cross section under varied fluid pressures within it and directly actuates the adjustable walls 77. Control of the tube pressure is had in the same manner as with the rigid walled tube. Obviously the tube's flexibility and strength of wall are to be chosen to meet the conditions it has to meet.

Again, in FIGS. 9 and 10, yet another modification of the actuating means is located in the space between the adjustable intermediate walls 77. In this case, screw threaded means 107 whose members respectively engage with the upper and lower adjustable walls 77 can be extended and retracted merely by rotating the one element, the nut 108, with respect to the other element, the stud 109. The stud is welded at one end to the upper adjustable wall extension 87 and passes through an aperture 110 in the lower adjustable wall extension 86 while the nut 108 bears against the inner face of the extension 86. For simultaneous operation, the nuts have secured to them sprockets 112. Studs and nuts are alternately provided

with right and left threads and a single actuating chain 111 extending alternately over one sprocket and under the next continuously about the ring as indicated in FIG. 9 serves to simultaneously and uniformly adjust them all.

A modification of auger feeding means, for assuring substantially uniform distribution of material to be pelleted, is pictured in FIGS. 11 and 12. Here instead of having double auger flights 53, 54 we have twine augers 115 and 116, each rotated about its own axis and in turn revolved about the die ring infeed housing 51. The mechanism through which this is achieved consists, as in the first form, of an upward axial extension 117 and the main drive shaft 35. This upward extension is of considerably greater diameter than extension 56 because the driving torque for augers 115, and 116 is to be derived through extension 117 instead of through a mounting cone such as 55. The upper end of this shaft extension 117 carries a transversely extending beam like frame 118 of channel, or box, across section. This frame at each outer end carries in bearings 119 the reduced upper ends of 20 shafts 115' and 116' of augers 115 and 116. Borne by the shafts between the bearings 119 are driving sprockets 126. Driving connection for revolving of the beam 118 is a splined hub connection 120 with shaft 117. Rigidly secured to the top of the housing 51 is a transverse beam 121 carrying, centrally, an elongated fixed journal 123 for the reduced upper end 117' of the drive shaft 117. This journal 123 passes downwardly through the top 25 of box beam 118, and the beam has a journal 128 about it. Fixed to the lower end of the bearing 123 is a sprocket 124 in the same plane as sprockets 126. A chain 125 extends around both sprockets 126 and engages sprocket 124 by an outside reach and so develops driving torque for augers 115, and 116 as the beam 118 and the augers are 30 revolved by shaft 117.

The material to be pelleted may be introduced to housing 51 in any desired manner, through the top, or through the side as indicated at 127. The closed box section 118 houses both sprockets and chains against fouling by the material being introduced and acted upon.

While this invention has been described in connection with a particular embodiment thereof, it will be understood that it is capable of modification, and this application is intended to cover any variations, uses, or adaptations following, in general, the principles of the invention and including such departures from the present disclosure as come within known or customary practice in the art to which the invention pertains, and as fall within the scope of the invention or the limits of the appended claims.

Having thus described my invention, what I claim is:

1. A ring die pelleting machine comprising a ring die structure and coacting rolling means relatively revolvable about a common axis, said ring die structure comprising a pair of spaced apart ring frame side plates, an annular series of separable abutting die cell units intervened between said side plates, each of said die cell units being integrally formed and embodying a side wall portion, a plurality of end wall portions and a pair of intermediate wall portions, said end wall portions extending cantilever fashion from opposite sides of said side wall portion at each end of said side wall portion, said intermediate wall portions extending cantilever fashion from opposite sides of said side wall portion midway between said end wall portions, each of said cell units individually forming less than a complete die cell but coacting with each other when abutted together in said annular series of units to define independently of said side plates a pair of annular series of radially extending die cells, each of which cells has one side defined by the side wall portion of one of said cell units, the other side defined by the side wall portion of an adjacent cell unit, one end defined by the abutting end wall portions of said one cell unit and said adjacent cell unit, and the other end defined by the abutting intermediate wall portions of said one cell unit and said adjacent cell unit.

2. A ring die pelleting machine as recited in claim 1 wherein said common axis extends vertically whereby one of said pair of side plates constitutes an upper side plate while the other of said pair of side plates constitutes a lower side plate, said upper side plate having an open inner periphery, a driving gear housing extending axially from said lower side plate, a vertically extending drive shaft journalled in said gear housing and extending coaxially with said common axis, a cone pointed vertically upwardly, means centering and mounting said cone on said drive shaft with the base of said cone located within said open inner periphery of said upper side plate, and auger flights carried on the surface of said cone.

3. A ring die pelleting machine as recited in claim 1 wherein each of said end wall portions of each of said cell units comprises a half end wall.

4. A ring die pelleting machine as recited in claim 1 wherein each cell of said pair of annular series of radially extending die cells has a material inlet mouth at the radially innermost portions of the cell units which coact to define the respective cells and a material discharge outlet at the radially outermost portions of the cell units which coact to define the respective cells, said side wall portions and said intermediate wall portions of each of said cell units having minimum thickness at said cell mouths and being progressively thicker radially outwardly from said cell mouths whereby the mouths of adjacent die cells adjoin each other and said adjacent cells diverge radially outwardly from their adjoining mouths toward their discharge outlets, said discharge outlets of adjacent cells being spaced apart from each other.

5. A ring die pelleting machine as recited in claim 4 wherein said end wall portions of said cell units project radially inwardly beyond said side wall portions and converge radially inwardly beyond said side wall portions, and said rolling means comprises rolls which enter between said radially inwardly projecting end wall portions.

6. A ring die pelleting machine as recited in claim 5 wherein said rolls have generally convex contoured peripheral faces whereby as the rolls pass the mouths of the respective die cells the portion of the roll faces toward the respective cells are normal to the cells.

7. A ring die pelleting machine comprising a ring die structure and coacting rolling means relatively revolvable about a common axis, said ring die structure comprising a pair of spaced apart ring frame side plates, an annular series of separable abutting die cell units intervened between said side plates, each of said cell units individually forming less than a complete die cell but coacting with each other when abutted together in said annular series of units to define independently of said side plates a pair of annular series of radially extending die cells, each of said cell units embodying a die cell fixed side wall portion extending radially relative to said common axis, a plurality of fixed die cell end wall portions formed integrally with said side wall portion and a pair of fixed intermediate cell wall portions formed integrally with said side wall portion, said end wall portions extending cantilever fashion from opposite sides of said side wall portion at each end of said side wall portion and being at least as long in radial dimension as said side wall portion, said fixed intermediate wall portions being substantially shorter in radial dimension than said fixed side wall and end wall portions and extending cantilever fashion from opposite sides of said side wall portion midway between said end wall portions, said fixed intermediate wall portions being disposed at the radially innermost part of said side wall portion, said side wall portion and said intermediate wall portions of each of said cell units having minimum thickness at the radially innermost parts thereof and being progressively thicker radially outwardly whereby the die cells defined by said abutting cell units diverge radially outwardly from each other, each of said cells having one side defined by the side wall portion of one of said cell

units, the other side defined by the side wall portion of an adjacent cell unit, one end defined by the abutting end wall portions of said one cell unit and said adjacent cell unit, and the other end defined by the abutting intermediate wall portions of said one cell unit and said adjacent cell unit, a pair of movable intermediate wall portions for each pair of abutting cell units, means connecting one end of each of said movable wall portions to said fixed side wall portions of each pair of abutting cell units at the radially outermost part of each pair of abutting fixed intermediate wall portions, each said pair of movable wall portions diverging radially outwardly from said connecting means and having spaced apart radially outermost ends, and means disposed between said movable wall portions at the radially outermost parts thereof for moving said movable wall portions respectively toward and away from said fixed end wall portions of said abutting cell units to vary the cross sectional size of the die cells.

8. A ring die pelleting machine as recited in claim 7 wherein said means connecting one end of each of said movable wall portions to said fixed side wall portions comprises pins formed integrally with said movable wall portions and sockets mating with said pins formed in said fixed side wall portions of said die cell units.

9. A ring die pelleting machine as recited in claim 7 wherein said movable wall portions have laterally projecting extensions formed thereon at their radially outer ends and said fixed side wall portions of said cell units have shoulders formed thereon at their radially outer ends and positioned to engage said movable wall extensions and limit the minimum cross sectional size of the die cells.

10. A ring die pelleting machine as recited in claim 7 wherein said movable wall portions have extension members extending radially therebeyond and angularly toward said fixed end wall portions of said cell units thereby projecting into the pathways of columns of material extruded through said cells to engage and break said columns of material into pellets.

11. A ring die pelleting machine comprising a ring die structure and coacting rolling means relatively revolvable about a common axis, said ring die structure comprising a pair of spaced apart ring frame side plates, an annular series of separable die cell units intervened between said side plates and abutting each other in planes radial to said common axis, each of said cell units individually forming less than a complete die cell but coacting with each other when abutted together in said annular series of units to define independently of said side plates two superimposed annular series of radially extending die cells with the respective cells of each series diverging radially

outwardly from each other and with the two series of cells diverging axially relative to each other, said cell units having integrally formed radially extending fixed die cell end wall and side wall portions and radially extending axially adjustable movable wall portions, said movable wall portions being disposed between said two annular series of die cells and being axially spaced apart at their radially outermost ends, and adjusting means arranged in a transaxial plane and disposed between said radially outermost ends of said movable wall portions, said adjusting means comprising axially extendable means individually and simultaneously acting upon each of said movable wall portions.

12. A ring die pelleting machine according to claim 11 in which the adjusting means comprises a relatively thick walled rigid annular tube engaged on one side with the adjacent adjustable wall of one series, and axially extending pistons reciprocating into and out of fitting openings to the hollow of said tube and having individual adjusting engagement each with one of adjustable walls of the other series.

13. A ring die pelleting machine according to claim 11 in which the adjusting means comprises extensible and retractable screw means intervened between juxtaposed pairs of adjustable walls together with common means for operating said screw means.

14. A ring die pelleting machine according to claim 11 in which the adjusting means comprises an expandable and collapsible tube whose opposite sides have a seated engagement each with the adjustable walls of one of superimposed series.
